HAND-OPERATED ABRADER

Atto N. Hanna, Atlantic Highlands, N. J.

Application November 28, 1945, Serial No. 631,297

1 Claim. (Cl. 51—185)

1

This invention relates to a hand-operated abrader and has special reference to the provision of a novel supporting block and enveloping abrading member.

The difficulty involved in the abrading or sandpapering operation in carpentry or any other form of handcraft is well known. To apply a flexibly backed abrasive element such as sandpaper or emery cloth to any surface with the hand alone not only imposes great strain on the hand, but also does not permit smooth application of the abrading element, even when expertly applied. The use of wooden blocks to act as supports for the sandpaper or emery cloth is an old expedient, but there are many disadvantages attendant upon such use. In particular might be mentioned the difficulty of obtaining a block suitably shaped for various sandpapering demands, the tendency of the sandpaper to slip from said block, particularly when pressure is applied, and the less efficient use of sandpaper when applied by such a block in that all of the abrasive surface cannot effectively be applied against the surface of the article to be smoothed.

It is a prime object of the present invention to provide a simple but effective supporting block for sandpaper and similar flexibly backed abrasive elements.

It is a further object of this invention to provide such a block wherein sandpaper consumption can be materially reduced by providing for effective use of the entire abrasive surface.

It is a further object of this invention to provide such a block wherein the sandpaper will not slide on the block, thus making the sanding operation much less difficult.

It is a further object of this invention to provide such a block wherein various sized supporting surfaces are provided to meet the various sizes and types of surface to which the sandpaper might be applied.

It is a further object of this invention to provide such a block wherein replacement of the worn-out sandpaper may be quickly and easily accomplished, even by the unskilled operator.

To the accomplishment of the foregoing objects and such other objects as may hereinafter appear, the present invention resides in the combination of a supporting block, a flexible abrasive strip, and expandable means as herein described and as defined in the appended claim.

In the appended drawing:

Fig. 1 is a perspective view of a preferred embodiment of the present invention;

Fig. 2 is a side view of a supporting block of

this embodiment with the flexible abrading element and the expandable member removed;

Fig. 3 is an end view of the supporting block shown in Fig. 2;

Fig. 4 is a perspective view of one type of expandable member that may be used; and

Fig. 5 is a perspective view of the continuous strip of an abrading element employed with the supporting block.

- 10 10. The invention consists of a supporting block, generally designated as A, which is so constructed as to be conveniently grasped by the operator's hand and at the same time to present to the surface to be abraded a suitably shaped support surface. This block is enveloped by a flexibly backed abrasive strip in continuous form, generally designated as B, which abrasive strip is supported by the block A with its abrasive surface outermost and is, during the abrading operation, held firmly between the support surface of the block A and the surface to be abraded. The abrasive strip B is releasably held under tension on the support block by a contractile and expandable means, generally designated as C.
- 15 20. In the embodiment of the invention disclosed generally in Fig. 1, and more in detail in Figs. 2 to 5, the supporting block A is provided with long, flat top and bottom walls 2 and 4, and short, rounded end walls 6 and 8, which walls comprise
- 25 30. the supporting surfaces for the flexibly backed abrasive strip B. The side walls 10 of this block are left exposed by the abrasive strip B and are provided with suitably shaped depressions 12, so that the block may be firmly grasped by the hand of the operator.

The contractile and expandable means C is here shown as affecting the end wall 8 in such a manner as to make it resiliently movable with respect to the block proper in order to permit the abrasive strip B to be readily removed and replaced, and in order to hold that strip under tension during the abrading operation. As illustrated in Fig. 4, it consists of a pusher-bar 14 with its outer surface—which is also the end wall 8—narrowly convex in shape. This bar is mounted on two supporting arms 16, which arms are adapted to loosely fit into holes 18 drilled into one end of the block proper. Loosely and slidably surrounding each arm 16 is a coil spring 20. 35 40 45 50 55 When the block proper, the pusher-bar 14, supporting arms 16, and the springs 20 are assembled, the upper end 22 of each spring abuts against the pusher-bar 14 and the lower end 24 is compressed against a shoulder 26 in the block formed by counter-sunk holes 28, concentric

with the holes 18, of greater diameter than the said holes, but of such a lesser depth as to permit unrestricted motion of the arms 16 in the holes 18 throughout the full range of compressibility of the springs 20. External pressure on the pusher-bar 14 in the direction shown by the arrow of Fig. 1 will compress the springs 20, thus decreasing the effective longitudinal dimension L of the block 10. When external pressure is released, the compressed springs 20 will force the pusher-bar 14 away from the block proper 10, thus increasing its longitudinal dimension L.

The flexibility backed abrasive strip B, adapted to be fitted over the block assembly as above described, is shown in Fig. 5. It consists of a strip 30, as of sandpaper, or emery cloth, or other flexibly backed abrasive material, cut to appropriate length and breadth from any suitable commercial product, and having its two ends 32 and 34 fastened together in any convenient manner, as for example, by means of an adhesive strip 36, in such a way as to form a continuous strip with the abrasive surface 38 externally disposed and the backing surface 40 internally disposed. While the dimensions of this strip must conform roughly to those of the support block, it will be apparent that by reason of the variable longitudinal dimension L of that block, variable because of the contractible and expansible pusher-bar of assembly C, these dimensions are not critical.

The tension exerted by the expansible means on the abrasive strip will tend to inhibit slipping between the block and the strip. However, in order to reduce the slipping tendency to a minimum, it has been found desirable to attach a friction lining 33 to the block on one or more of those surfaces where the block and the sandpaper are in contact, which strip offers a highly frictional surface to the backing surface 40 of the abrasive strip, thus preventing the abrasive strip from slipping during use of the device. This lining may be of asbestos, felt, or any other suitable frictional material.

The manner of use of this device should be apparent from the above description. A strip of, for example, sandpaper of suitable dimension is cut from any commercial source, the free ends are fastened together and the now continuous strip is then fitted over the support assembly so as to envelope all but the side walls. The device is then ready for operation and any of the support surfaces can be used for sanding or abrading. When the sandpaper surface being used has been worn to a point of non-effectiveness, the expansible member may be depressed and the sandpaper rotated with respect to the support assembly until a fresh sandpaper surface is presented to the work. In the embodiment illustrated, if one flat surface becomes worn, the device may merely be turned upside down, thus providing for effective use another unworn long surface, and the device still presents features of convenience and non-slippage between the sandpaper and the block. If sanding is necessary on narrow surfaces or depressed areas, the rounded ends of the block may be used, and as the sandpaper becomes worn, a slight rotation of the sandpaper with respect to the block will provide an unworn abrasive surface ready for use. In the embodiment shown, the convex pusher-bar provides an extremely narrow sup-

port which is very advantageous in sanding very narrow surfaces such as edges or for getting into tight corners.

While I have disclosed the preferred form of construction of this hand-operated abrader, it will be obvious that many changes may be made in the structure without departing from the invention defined in the following claim.

I claim:

A hand-operated abrader comprising a supporting block having end walls, opposite side walls and long flat top and bottom walls, said top and bottom walls being parallel, said opposite side walls having hand hold depressions, one of said end walls being smoothly and bluntly curved and the other of said end walls having a central flattened portion, said block having a pair of holes extending inwardly parallel to said top and bottom walls from said flattened portion of said other of said end walls, said holes being provided with shoulders disposed inwardly from said flattened portion, a friction lining affixed to said top and bottom walls and said smoothly rounded end wall, a removable flexibly backed abrasive strip in continuous form enveloping the top, bottom and end walls of said block, said enveloped top and bottom and said other of said end walls being exposed for abrasive action, the side walls of said block being exposed to be grasped by the operator's hand; a sharply curved pusher bar provided with a pair of supporting arms each adapted to fit within one of said holes in said supporting block; and a coil spring loosely surrounding each of said supporting arms, each of said springs adapted to have one end seated against the shoulder in the appropriate holes and the other end active against said pusher bar, said pusher bar being located between said block and said abrasive strip and resiliently urged by said abrasive strip and resiliently urged by said springs into contact with the interior of said continuous abrasive strip so as to be frictionally active thereupon to releasably hold the same under tension in non-slipping relationship to said block, the strip being rotationally movable over the top, bottom and end walls of the block and over said pusher bar for bringing a fresh abrasive surface thereof over any desired one of said walls only when said springs are contracted, the top and bottom walls of said abrader in conjunction with said abrasive strip defining broad flat abrasive surfaces, the bluntly curved end wall of said block in conjunction with said abrasive strip defining a bluntly curved abrasive surface, and said pusher bar in conjunction with said abrasive strip defining a curved abrasive surface of extreme narrowness.
